Attorney

UNITED STATES PATENT OFFICE

LLOYD L. LOGAN, OF CALEXICO, CALIFORNIA

OIL BURNER

Application filed April 7, 1930. Serial No. 442,284.

This invention relates to fuel oil burners, and it has for its object to provide a simple and inexpensive device, particularly adapted for use in small heaters and boilers, and constructed in such manner that a more efficient atomization of the oil, and, consequently, a more efficient and complete combustion can be had, than is possible with known structures.

10 The figure shown in the accompanying drawing is a view partly in side elevation, and partly in section of a burner constructed in accordance with the invention.

In the drawing, 5 designates a fuel oil supply line having a control valve 6, and a suitable strainer structure 7, included in its length. An oil line 8 leads from the valve 6 and terminates in a curved tip portion 9. The terminal end of this curved tip portion lies at the angle shown, and in front of an air or steam nozzle 10, which receives its supply of air, steam or like atomizing agent, through pipe 11, which has a control valve 12, in its length. The nozzle or tip 10 is slidably disposed upon the end of the pipe 11, and it may be adjusted therealong by a rod 13, which has threaded engagement with an ear 14, standing from pipe 11. The forward end of the rod is provided with collars 15, which lie upon opposite sides of a boss 16, of the nozzle 10, the outer end of the rod 13 passing through said boss.

30 Thus, the position of the nozzle 10, with respect to the terminal end of the tip 9, may be adjusted, at will.

In operation, the atomizing agent leaves the nozzle 10 and discharges against the rear side of the oil tip 9, creating a zone of negative pressure at the discharge end of the oil tip. This negative pressure draws the oil or material to be vaporized to the outer edges of the oil tip 9 in a thin even film. It will be observed that the oil tip 9 is cut off so that its discharge end lies at an angle of approximately 45° to the general line of the atomizer tip at its extremity. This results in the formation of an elongated opening in the oil tip. The oil line 8 and the oil tip 9 are constructed of tubing of relatively light gauge, the thin walls of which permit such disposi-

tion of the parts that there is only a very little distance between the oil tip and the atomizing agent, thus effecting quicker contact between the two. The atomizing agent spreads in fan shape as it leaves the oil tip, 55 making possible a greater distribution of the oil for combustion purposes. It is to be noted that my arrangement is such that the jet of atomizing agent is not discharged directly into the oil but acts to create a zone of negative pressure and this in turn causes the oil to be spread evenly from every side of the oil tip opening. By virtue of this construction, I am able to secure perfect atomization, and I am able to operate the burner 60 under a lower steam or air pressure than has heretofore been possible. By dispositioning the parts as shown, a more perfect blaze is attained, both with respect to its shape, evenness of heat and completeness of combustion 65 than is possible with any other burner with which I am familiar. While the construction herein shown and described is of particular utility in connection with the atomization of fuel oils, in oil burners, the principle involved is of equal utility in connection with spraying apparatus, in general. It is of utility in connection with the spraying of insecticides for use upon trees, plants, flowers, and other shrubery. It is also of utility in 70 connection with the spraying of paints, and, in fact, in any relation where fine atomization is desirable.

75 It is to be understood that the invention is not limited to the precise construction set forth, but that it includes within its purview whatever changes fairly come within either the terms or the spirit of the appended claim.

Having described my invention, what I claim is:

An oil burner comprising an oil line which extends substantially horizontally from a source of oil supply toward the point of combustion for a portion of its length, and is then continued for the remainder of its length in 95 downwardly bowed form, an atomizing line extended substantially horizontally and above the first named line and across the concavity formed by the shape of the oil supply line, a nozzle upon the atomizing line within 100

the concave portion of the oil supply line said nozzle discharging against the rear side of the oil supply line adjacent the end thereof, a rod extending in substantial parallelism with the atomizing line, an element carried by the atomizing line with which said rod has threaded engagement, and means for connecting the forward end of said rod to the nozzle in such manner as to permit the rod to turn while causing the nozzle to move with the rod axially of the atomizing line and toward and from the rear side of the tip of the oil line.

In testimony whereof I affix my signature.
